ATTORNEY.

UNITED STATES PATENT OFFICE.

TUDOR C. CORK, OF NEW YORK, N. Y., ASSIGNOR TO AMERICAN CAR AND FOUNDRY COMPANY, OF NEW YORK, N. Y., A CORPORATION OF NEW JERSEY.

RAILWAY TRAPDOOR LOCK MECHANISM.

1,405,496.

Specification of Letters Patent. Patented Feb. 7, 1922.

Application filed November 30, 1921. Serial No. 518,897.

To all whom it may concern:

Be it known that I, TUDOR C. CORK, residing at New York city, county and State of New York, and being a citizen of the United States, have invented certain new and useful Improvements in a Railway Trapdoor Lock Mechanism, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a cross-section of the end sill of a passenger-train car vestibule platform showing my improved trap door locking and opening mechanism in operative position;

Figure 2 is an enlarged plan view of the mechanism showing a portion broken away along line 2—2 of Fig. 5 to better illustrate the disposition of the enclosed working parts;

Figure 3 is a longitudinal central section through the mechanism illustrated in Fig. 2 showing the locking bolt and door lifting lever assembled with the operating plunger;

Figure 4 is a vertical sectional view taken on line 4—4 of Fig. 3 looking in the direction indicated by the arrow; and

Figure 5 is a similar view taken on line 5—5 of Fig. 3 through the door retaining portion of the bolt and the door lifting lever.

My invention relates to trap door opening and locking mechanism, and particularly to such mechanism adapted for use in connection with platform trap doors of passenger-train cars.

One object of my invention is to provide means for releasing and partially raising platform trap doors from their horizontal closed position over the platform steps.

Another object is to provide means for partially raising such doors automatically upon manipulation of associated door locking elements.

In said drawings, 10 represents the vestibule end wall; 11, the vestibule platform floor upon which is mounted the platform door locking mechanism 12 adjacent a free

edge of a trap door 13 adapted for opening 55 toward the end wall of the car body.

The trap door may be released by an operator on the platform by means of the mechanism 12. The mechanism is provided with an operating plunger 14 extending upwardly from within the casing 15, the parts being actuated upon depressing the plunger 14. For this purpose, the plunger is provided with an enlarged portion 16 shaped to afford an inclined plane face 17 for engagement with a complementary inclined face 18 on the sliding bolt 19 within casing 15 and in the path of downward movement of inclined face 17 on the plunger. The plunger 14 is supported within the casing 15 through the medium of the inclined face 18 on the bolt, said face being held in supporting engagement with the plunger face 17 by the expansive power of springs 20 supported within the casing 15 upon studs 21 on rear wall 22 of the casing and studs 23 on side extensions 24 on the bolt 19. The casing is tubular in cross-section, having a top wall 25, side walls 26, and bottom wall 27. Rear wall 22 closes one end of said casing, but the opposite end is open to receive the various elements of the lock mechanism. The top wall 25 and the bottom wall 27 of the casing are provided respectively with aligned openings 25^a and 27^a to receive and guide the plunger rod 14, opening 27^a being somewhat larger than opening 25^a to admit plunger 14 over its enlargement 16.

The bolt moves between the walls of the casing and comprises a skeletonized body having a stop wall 28 extending between the side walls 26 of the casing and providing abutments for one end of the springs 20, said partition having a portion thereof functioning to check abnormal outward movement of the bolt upon engagement with another part hereinafter to be described. The bolt is also provided with a nose portion 29 beveled on its upper outer side as shown at 30 and spaced from stop wall 28. Portions 28 and 29 are connected by spaced plunger yoke members 31 extending from the nose piece 29 rearwardly to connect with the inclined portion 18 and to guide and connect with plunger 14.

The bolt is so arranged within the casing 15 that beveled portion 30 thereof protrudes beyond the casing as shown in Figs.

1, 2, and 3, and in the path of the free edge of the trap door. Pivotally held within the casing 15 by pin 32 is a bell-crank lever 33 having an arm 34 extending upwardly between bolt portions 28 and 29 and a trap door lifting arm 35 positioned below and spaced from bolt portion 29 and under the free edge of the trap door, so that the trap door when closed will be held with its free edge in the space thus provided.

As shown in Fig. 3, arm 34 of the bell crank lever 33 bears against stop wall 28 and serves to check abnormal outward movement of the bolt 19 under the pressure of springs 20. The tendency of the bolt to move outwardly under the action of the springs will cause the inclined wall portion 18 of the bolt to bear with sufficient pressure against the inclined plunger face 17 to support the plunger 14 in the full line position shown in Fig. 3, with its enlargement 16 lodged within pocket 36 in the top wall 25 of the casing, said pocket being designed to prevent rotation of the plunger rod to insure that the inclined plunger face 17 will always be presented towards inclined wall 18 on the bolt and in position to engage the same. It will be noted that arm 35 rests against floor 27 of the casing, and that the upwardly extending arm 34 of the bell crank 33 engages stop wall 28 of the bolt but is spaced from nose portion 29 to permit retraction of the bolt from its position over the free edge of the trap door in advance of trap door lifting movement of arm 35.

In operation, assuming the parts to be in the full line positions shown in Figs. 2 and 3, a downward movement of plunger 14 will cause the inclined face 17 on the plunger rod enlargement 16 to slide upon inclined face 18 on the bolt and force said bolt away from the trap door 13 until the nose piece 29 recedes from its position above the free edge of the trap door and is drawn into its retracted position within the casing 15 as indicated in Fig. 3. During the progress of the bolt 19 to full retracted position the rear face of the nose piece 29 will strike arm 34 of the bell crank lever 33 causing said lever to rotate upon its pivot 32 and carry the door opening arm 35 upwardly against the underside of trap door 13 to partially open the same, at the completion of which operation plunger rod 14 will have been depressed to the broken line position indicated in Fig. 3.

Upon release of plunger rod 14 the force of the expanding springs 20 will propel the bolt 19 towards trap door 13 until the bolt 60 stop wall 28 engages upstanding arm 34 of bell crank lever 33 when further outward movement thereof is checked, bringing the parts in position to be again retracted as described.

65 It will be noted that the skeletonized char-

acter of the bolt construction admits of a close operating relation between the moving parts, permitting the bolt to receive within its confines portions of the spring elements, the plunger rod, and the trap door lifting lever, including means for checking abnormal outward movement of the bolt.

To insure stability of the mechanism during all stages of operation and to firmly secure same to the floor of the car platform, 75 casing 15 is provided with integral flanges 37 projecting outwardly from side walls 26 thereof and perforated as at 38 to receive suitable fastening devices.

What I claim is:

1. A locking mechanism for platform trap doors comprising a casing secured adjacent the free edge of the trap door, a trap door engaging bolt slidable within said casing, and means associated with said bolt for 85 checking abnormal outward movement thereof, said means being operable by said bolt to partially open the trap door.

2. A locking mechanism for platform trap doors comprising a casing secured adjacent the free edge of the trap door, a trap door engaging bolt slidable within said casing, and means associated with said bolt for checking abnormal outward movement thereof, said means being operable by said 95 bolt to partially open the trap door, and bolt retracting means.

3. In a locking mechanism for platform trap doors comprising a casing secured adjacent the free edge of the trap door, a bolt 100 slidable within said casing having an end adapted to rest in position above said trap door, means for retracting said bolt, and other means associated with said bolt for checking abnormal outward movement 105 thereof, said bolt checking means being operable by the bolt to partially open the trap door.

4. In a platform trap door locking mechanism comprising a casing secured adjacent 110 the free edge of the trap door, a skeletonized bolt slidable within said casing and having a nose portion adapted to engage the trap door, and means associated with said bolt for checking abnormal outward movement 115 thereof, said means being operable upon engagement with the nose portion of said bolt to partially open the trap door.

5. In a platform trap door locking mechanism comprising a casing secured adjacent 120 the free edge of the trap door, a skeletonized bolt slidable within said casing and provided with a nose portion adapted to engage the trap door and a wall portion spaced from said nose portion, and means associated with 125 said wall portion to check abnormal outward movement of said bolt, said means being operable by the nose portion of the bolt to partially open the trap door.

6. The combination with a trap door, of 130

a locking mechanism therefor comprising an outer casing, a trap door engaging bolt slideable within said casing, and bolt checking means, said means being operable by said 5 bolt to partially raise the trap door.

7. The combination with a trap door, of a locking mechanism therefor comprising an outer casing, a trap door engaging bolt slideable within said casing, means operable by 10 said bolt for partially raising the trap door, said means being adapted to check abnormal outward movement of said bolt.

8. In a platform trap door locking mechanism including a casing secured adjacent 15 the free edge of the trap door, a bolt slideable within said casing and having one end in position above the trap door when closed, and a bell crank lever operable by said bolt to partially open the trap door, said bell 20 crank lever being further adapted to check abnormal outward movement of said bolt, and bolt retracting means.

9. In a platform trap door locking mechanism including a casing secured adjacent 25 the free edge of the trap door, a skeletonized bolt slideable within said casing, spring abutments on said bolt and casing, a spring within 30 said bolt and casing and seated against said abutments, bolt actuating mechanism in the casing at one end of said bolt, and means operable upon actuation of said bolt to partially open the trap door, said means being adapted to check abnormal outward movement of said bolt.

35 10. In a platform trap door locking mechanism including a casing secured adjacent the free edge of the trap door, a skeletonized bolt slideable within the casing, spring abutments on said bolt and casing, and a spring 40 within said bolt and casing and seated against said abutments, and bolt retracting means.

11. In a platform trap door locking mechanism comprising a casing secured adjacent 45 the free edge of the trap door, a skeletonized bolt slideable within the casing in position to engage the trap door, spring abutments on said bolt and casing, a spring within said bolt and casing and seated against said abutments, bolt retracting means, and means operable by said bolt to partially open the trap door.

55 12. In a platform trap door locking mechanism comprising a casing secured adjacent the free edge of the trap door, a skeletonized bolt slideable within the casing in position to engage the trap door, spring abutments on said bolt and casing, a spring within said bolt and casing and seated against said abutments, bolt retracting means, and means

operable by said bolt to partially open the trap door, said means being further adapted to check abnormal outward movement of said bolt upon release of the bolt retracting means.

65 13. In a platform door locking mechanism including a casing secured adjacent the free edge of the trap door, a skeletonized bolt slideable within said casing, bolt retracting means, and a yoke portion on said bolt embracing said bolt retracting means.

70 14. In a platform door locking mechanism including a casing secured adjacent the free edge of the trap door, a bolt slideable within said casing, bolt retracting means comprising a plunger having an inclined face portion, and a yoke portion on said bolt embracing said plunger and having an inclined face portion adapted for engagement with the inclined face portion on the plunger.

75 15. In a platform trap door locking mechanism comprising a casing secured adjacent the free edge of the trap door, spring abutments on the casing, a skeletonized bolt slideable within said casing and having an 80 extended movement checking wall providing spring abutments, springs within said bolt and casing supported on said abutments, yoke members extending rearwardly from said checking wall, and bolt retracting 85 means extending through said casing and between said yoke members.

90 16. In a platform trap door locking mechanism comprising a casing secured adjacent the free edge of the trap door, a skeletonized bolt slideable within said casing and having a nose portion adapted to engage the trap door, and means associated with said bolt for checking abnormal outward movement thereof and spaced from said nose portion, 95 said means being operable upon engagement with the nose portion of said bolt to partially open the trap door.

100 17. In a platform trap door locking mechanism comprising a casing secured adjacent the free edge of the trap door, a skeletonized bolt slideable within said casing and having a nose portion adapted to engage the trap door, and means associated with said bolt for checking abnormal outward movement 105 thereof and spaced from said nose portion, said means being operable upon subsequent engagement with the nose portion of said bolt to partially open the trap door.

110 In witness whereof I have hereunto set my 115 hand in the presence of two witnesses.
